BENJAMIN W. SUNDE, OF LONG BEACH, CALIFORNIA, ASSIGNOR TO BLACKWELL & SUNDE, INCORPORATED, OF LONG BEACH, CALIFORNIA, A CORPORATION OF CALIFORNIA

DENT REMOVER

Application filed February 17, 1930. Serial No. 429,053.

This invention relates to a device for straightening pipe or other tubular parts and relates more particularly to a device for removing indentations and irregularities from 5 pipe, casing, etc.

Various types of devices are employed in removing indentations and irregularities from pipe. One form of device used for straightening pipe includes shoes to be inserted in a pipe, and cylinder and piston means for spreading or forcing the shoes apart to force them into engagement with the interior of the pipe. In the form of device referred to, the fluid pressure operating 10 means for forcing the shoes apart is developed at the exterior of the pipe or at the end of the pipe and is supplied to the fluid pressure means by a conduit. As the shoes must necessarily be placed or arranged in the 15 pipe to be in operating position, and the fluid pressure means or cylinder and piston means for operating the shoes is between the shoes or in close proximity to the shoes, it is necessary to provide a conduit, for delivering the 20 fluid under pressure to the fluid pressure means, that is sufficiently long to extend from the pump for developing fluid pressure at the end of the pipe, to the fluid pressure means adjacent the shoes. When a device of the 25 type mentioned is to be used in long lengths of pipe, the fluid conduit must be very long and the device is more or less inconvenient and difficult to handle and control.

It is a general object of the invention to 30 provide a simple and compact device for removing irregularities and indentations from pipe, and the like, that is in the form of a complete unit adapted to be bodily inserted in a pipe and adapted to be operated and controlled from the end or exterior of the pipe.

Another object of the invention is to provide a dent removing device of the character mentioned that is in the form of a compact unit adapted to be inserted in a pipe that includes a jack or cylinder and piston mechanism 45 for forcing a shoe against the interior of the pipe and embodying a pump for supplying fluid under pressure to the cylinder and piston mechanism.

Another object of the invention is to pro-

vide a device of the character mentioned in which the pump is arranged adjacent the cylinder and piston mechanism and is adapted to be manually or mechanically operated through an operating member adapted to be 55 connected with the pump and adapted to project from an end of the pipe.

Another object of the invention is to provide a device of the character mentioned in which pressure in the cylinder of the jack, or 60 cylinder and piston mechanism, may be released by means of a valve controlled by a rod adapted to project from an end of the pipe.

Another object of the invention is to provide a device of the character mentioned in which the member for operating the pump and the control rod for the valve are detachable from the device and may be provided in various lengths so that the device may be 65 conveniently operated and controlled in various positions in pipes of various lengths.

Another object of the invention is to provide a dent removing device of the character mentioned that is constructed so that it is 70 adaptable to be used in pipes of various diameters.

Other objects and features of the invention will be best and more fully understood from the following detailed description of a typical form and application of the invention, throughout which description reference is had to the accompanying drawings, in which:

Fig. 1 is an end view of the device provided by this invention showing it arranged in a 85 tubing or pipe. Fig. 2 is a side elevation of the device in a pipe. Fig. 3 is an enlarged vertical detailed sectional view of the device, and Fig. 4 is an enlarged vertical sectional view of the valve mechanism of the pump 90 embodied in the present invention.

The device provided by this invention includes, generally, a body or base 10 adapted to be arranged against the interior of a pipe, or the like, a jack or cylinder and piston mechanism 11 on the base for operating a shoe 12 into engagement with the interior of a pipe, a fluid reservoir 13 on the base 10, a pump 14 for supplying fluid under pressure to operate the cylinder and piston mechanism 11, and 100

means 15 for releasing the pressure in the means 11.

The body or base 10 is provided to carry the other parts of the device and is adapted to be arranged or seated against the inner wall of a tubular part such as a pipe P. The base 10 is preferably elongated so that it is adapted to be arranged longitudinally or axially in the pipe P and is shaped to effectively seat against the curved interior of the pipe. The base 10 is provided with a curved outer side 16 and a flat inner or upper side 17. In accordance with the invention the base is proportioned so that it has a large outer side 17 which is adapted to seat on a substantial portion of the interior of the pipe so that the base does not distort the pipe when the shoe 12 is forced against the interior of the pipe. The base 10 is shaped and proportioned so that there is considerable space between its inner side 17 and the wall of the pipe above or opposite the side 17. It is preferred that the base 10 occupy only a small portion of the cross sectional dimension of the pipe.

In accordance with the invention, means is provided for adapting the base to be effectively seated on the inner walls of pipe of various diameters. The curved or outer side 16 is shaped to effectively seat on the interior of a pipe of a given diameter and fill-in shoes 18 having curved outer sides to conform to the interior of a pipe P of larger diameter may be removably mounted on the curved outer side 16. The shoes 18 are provided at longitudinally spaced points on the side 16 and extend circumferentially of the side. The shoes 18 may be detachably secured to the base 10 by any suitable means. Spacer rods 19 may be arranged between the shoes 18. It will be obvious that shoes 18 of various sizes may be provided to adapt the device to be used in pipes of various diameters.

The jack or cylinder and piston means 11 is provided to operate the shoe 12 outward relative to the base 10 to engage a dented or irregular wall of the pipe. The means 11 includes a cylinder 21 carried by the base 10 and a plunger or piston 22 slidably carried in the cylinder 21 and carrying the shoe 12.

The cylinder 21 may be a plain tubular part having one end screw threaded into an opening or socket 23 in the flat side 17 of the base. The central longitudinal axis of the cylinder 21 is preferably diametric relative to the curvature of the curved outer side 16 of the base. The piston 22 is slidably carried in the cylinder 21 and carries the shoe 12 at its upper or outer end. The plunger 22 may project from the outer end of the cylinder 21 and may have a flat outer end to receive the shoe 12. A cup leather 24 may be provided on the inner end of the piston or plunger 22 to seal against the wall of the cylinder. The cup leather 24 may be retained on the plunger 22 by a disc 25 clamped against

the cup leather by a bolt 26 screw threaded into an opening in the inner end of the plunger.

The shoe 12 is removably mounted on the outer end of the plunger 22 outwardly of the end of the cylinder. In the particular case illustrated, the shoe 12 has an outer face curved to conform to the normal configuration of the interior of the pipe P. The shoe 12 may be detachably connected with the plunger by means of a stud 27 carried by the shoe and screw threaded into an opening in the outer end of the plunger 22. The inner side of the shoe 12 may be flat to effectively seat on the end of the plunger 22. Shoes 12 of various sizes having outer faces of various configurations may be mounted on the plunger 22 to adapt the device for use in various types and sizes of pipe. In the particular case illustrated in the drawings the outer side of the shoe 12 is curved concentrically with the outer sides of the shoes 18 and has the same diameter of curvature as the curved outer sides of the shoes 18.

A central longitudinal passage 28 is provided through the plunger 22. The passage 28 communicates with the opening carrying the bolt 26 and a longitudinal opening 29 is provided in the bolt 26 to register with the passage 28. The upper end of the passage 28 communicates with the opening carrying the stud 27. A socket or enlargement 30 is provided at the upper or outer end of the passage 28 below the stud 27. A lateral opening 31 is formed in the head of the bolt 26 to communicate with the passage 28. The opening 31 extends to the exterior of the head of the bolt at a point adjacent the disc 25.

The passages 28 and 29 are provided to bleed or remove air or gas from the cylinder 21 when the device is initially operated or when air or gas accumulates in the cylinder. A ball valve 32 is arranged in the enlargement 30 of the passage 28 to normally close the passage. A lock or clamp screw 33 may be threaded into the enlargement 30 to normally clamp the valve 32 into sealing engagement with a seat formed in the passage to close the passage.

The reservoir 13 is mounted on the base 10 and is provided to contain fluid, for instance oil, for operating the plunger 22. The reservoir 13 may include a cylindrical body 34. The body 34 of the reservoir may have its upper end closed by a head or cover plate 35 and its lower end may seat or extend into an annular recess 36 in the outer side 17 of the base. In accordance with the invention the body 34 of the reservoir is arranged on the base 10 adjacent the cylinder 21. Clamping bolts 37 may extend through the cover plate 35 and longitudinally through the reservoir to retain the body 34 in position. The lower ends of the bolts 37 may be screw threaded into openings in the outer side 17

of the base and heads may be provided on the outer ends of the bolts to clamp the cover plate 35 against the upper end of the body 34. Diametrically opposite bearing lugs 38 are provided on the interior of the body 34 adjacent its outer end.

The pump 14 is provided to supply fluid under pressure to the cylinder 21 to operate the piston or plunger 22. In accordance with the invention the pump 14 is adapted to be manually operated; it being obvious that the pump may be mechanically operated without departing from the spirit of the invention. The pump 14 may be an accepted type of pump suited for use in connection with the cylinder and piston mechanism 11. In the particular case illustrated the pump 14 includes a cylinder 40 mounted on the base 10 and arranged within the reservoir 13, a plunger or piston 41 slideable in the cylinder 40, intake and outlet valves 42 and 43, respectively, for the cylinder 40, and a crank shaft 44 projecting from the reservoir 13 and adapted to receive an operating member 45. The cylinder 40 of the pump may be axially and concentrically arranged within the body 34 of the reservoir 13 and may have its inner end screw threaded into an opening 46 in the inner side 17 of the base 10. The piston 41 extends through the outer end of the cylinder 40 to project into the interior of the body 34 of the reservoir. The outer or projecting end of the piston 41 may be enlarged and may have spaced yoke parts 48. A suitable packing or cup leather 49 may be provided on the inner end of the piston 41. A packing gland or stuffing box 50 may be provided at the upper end of the cylinder 40 to pack around the piston 41.

The valves 42 and 43 are shown arranged in a valve block 51 carried in the inner end of the opening 46. The valves 42 and 43 may be in the nature of spring pressed ball valves. The valve 42 is provided to control the passage of fluid through an opening 52 communicating with the interior of the reservoir 34 and the lower portion of the opening 46. The valve 42 may be arranged in a passage in the block 51 communicating with the cylinder 40 and the opening 46. The valve block 51 closes the lower end of the cylinder 40 so that fluid is prevented from entering the end of the cylinder from the lower portion of the opening 46. The outlet valve 43 controls the passage of fluid through a passage 53 communicating with the cylinder 21 and the cylinder 40.

The crank shaft 44 has axially aligned portions 54 rotatably carried in openings 55 in the bearing lugs 38. Spaced eccentric arms or crank arms are provided on the shaft 44 within the reservoir body 34 and carry an eccentric 56. A connecting rod 57 operatively connects the eccentric 56 and the piston 41. The rod 57 may be connected with the yoked

parts 48 by a suitable pin. One of the portions 54 of the crank shaft 44 has a polygonal part 58 projecting outwardly from the body of the reservoir 13 through an opening 55. The projecting part 58 of the crank shaft is adapted to be engaged by the operating member 45. The member 45 is provided at its end with a polygonal socket 59 to receive the polygonal part 58. The member 45 is detachable from the part 58. The member 45 is preferably made sufficiently long to extend from an end of the pipe P to the part 58.

The means 15 for releasing the pressure in the cylinder 21 includes a valve 60 operable to control the passage of fluid through a passage 61 in the base 10. The passage 61 extends between or communicates with the cylinder 21 and the reservoir 13. The valve 60 may be in the nature of a needle valve having a pointed inner end adapted to cooperate with a suitable seat formed in the passage 61. The body or stem of the valve 60 is screw threaded into an opening 67 in an end of the base 10 and projects outwardly from the base. The stem of the valve 60 preferably projects from the same end of the base 10 as the part 58 of crank shaft. The projecting portion of the valve 60 has a transverse pin 62 extending through it and projecting from its opposite sides. The pin 62 is adapted to be engaged by a control rod 63 for operating the valve. The rod 63 is forked at its end to cooperate with the pin 62 to rotate the valve 60. The control rod 63 is made sufficiently long to extend from the device to an end of the pipe P. It will be obvious that members 45 and control rods 63 of various lengths may be provided so that the device may be operated at any desired points in pipes of various lengths.

In operation the device may be arranged at any desired point within a pipe by means of the member 45 or by any other means. When the device is positioned as desired, so that the shoe 12 is in position to engage an indentation, or the like, the operating member 45 may be rotated to operate the pump 40. The pump 40 supplies fluid under pressure to the cylinder 21, to operate the plunger 22 outwardly. It will be seen that the shoe 12 may be forced into pressure engagement with the interior of the pipe to restore the pipe to its normal configuration. When it is desired to release the pressure from the cylinder 21, the control rod 63 may be rotated to unseat the valve 60 to allow fluid to flow through the passage 61 from the cylinder 21 into the reservoir 13. It is to be noted that the passages 28 and 29 and the valve 32 provide a means for removing air that may accumulate in the cylinder 21. The stud 27, valve 32 and screw 33 may be removed and the pump operated so that air will be forced from the cylinder 21 through the passage 28. The screw and valve may be replaced when

oil commences to flow from the passage 28. It is to be noted that the device provided by this invention is in the nature of a compact unitary construction that may be conveniently and easily operated in pipes of various diameters and lengths.

Having described only a typical preferred form of my invention, I do not wish to limit myself to the specific details set forth, but 10 wish to reserve to myself any changes or variations that may appear to those skilled in the art or fall within the scope of the following claims.

Having described my invention, I claim: 15 1. A device of the character described including, a base adapted to be arranged within a pipe, a cylinder on the base, a piston slide- 20 able in the cylinder, a shoe operable into engagement with the interior of the pipe by the piston, a reservoir on the base adjacent the cylinder, a pump adjacent the cylinder for supplying fluid pressure to operate the piston, an operating member for the pump adapted to extend to an end of the pipe, and 25 means for releasing pressure from the cylinder.

2. A device of the character described including, a base adapted to be arranged within a pipe, a cylinder on the base, a piston slide- 30 able in the cylinder, a shoe operable into engagement with the interior of the pipe by the piston, a reservoir on the base adjacent the cylinder, a pump adjacent the cylinder for supplying fluid pressure to operate the piston, an operating member for the pump adapted to extend to an end of the pipe, and 35 means for releasing pressure from the cylinder, including a valve to control the passage of fluid from the cylinder to the reservoir, 40 and a control stem for the valve.

3. A device of the character described including, a base adapted to be arranged within a pipe, a cylinder on the base, a piston slide- 45 able in the cylinder, a shoe operable into engagement with the interior of the pipe by the piston, a reservoir on the base adjacent the cylinder, a pump adjacent the cylinder for supplying fluid pressure to operate the piston, an operating member for the pump 50 adapted to extend to an end of the pipe, and means for releasing pressure from the cylinder, including a valve, and a control stem detachably connected with the valve and adapted to extend to an end of the pipe.

55 4. A device of the character described including, a base adapted to be arranged within a pipe, a cylinder on the base, a piston slide- 60 able in the cylinder, a shoe operable into engagement with the interior of the pipe by the piston, a reservoir on the base adjacent the cylinder, a pump adjacent the cylinder, and means for removing gas from the cylinder including a valve arranged in a passage in the piston.

65 5. In a pipe straightening device adapted

to be arranged completely within a pipe, a base to seat on the interior of the pipe, a cylinder on the base, a piston slideable in the cylinder, a shoe on the piston adapted to be operated into engagement with the interior of the pipe, a fluid-reservoir on the base adjacent the cylinder, a pump on the base in the reservoir for developing pressure to operate the piston, an actuating member detachably connected with the pump and adapted to extend to an end of the pipe, a valve operable by rotation for releasing pressure from the cylinder, and a detachable stem for the valve adapted to extend to an end of the pipe.

In witness that I claim the foregoing I 80 have hereunto subscribed my name this 27th day of December, 1929.

BENJAMIN W. SUNDE.
